UNITED STATES PATENT OFFICE.

JESSE E. ETHERTON, OF CHICAGO, ILLINOIS.

RAIL-JOINT.

1,114,453.

Specification of Letters Patent.

Patented Oct. 20, 1914.

Application filed August 5, 1913. Serial No. 783,113.

To all whom it may concern:

Be it known that I, JESSE E. ETHERTON, a citizen of the United States, residing at Chicago, in the county of Cook and State of Illinois, have invented new and useful Improvements in Rail-Joints, of which the following is a specification.

The present invention relates to improvements in rail joints, the object being to so construct and arrange the meeting ends of two rails as to provide an interlocking connection between the said rails, and the improvement resides in the construction, combination and arrangement of parts set forth in the following specifications and falling within the scope of the appended claims.

In the drawings: Figure 1 is a side elevation of a rail joint constructed in accordance with the present invention, Fig. 2 is a top plan view of the same, Fig. 3 is a sectional view on the line 3—3 of Fig. 1, Fig. 4 is a sectional view on the line 4—4 of Fig. 2, Fig. 5 is a sectional view on the line 5—5 of Fig. 1, Fig. 6 is a detail perspective view of one of the rail ends, Fig. 7 is a similar sectional view of the coating rail end, and Fig. 8 is a view illustrating the manner of forming the joint between the rails.

The rails R—R are of the ordinary construction. The head of the rail R terminates in an inclined wall 1 which is arranged in a plane with the inclined upper portion of the web of the rail, or that portion which terminates with the head and which is indicated by the numeral 2. The head at its end is formed with a dove-tailed slot or opening 3, the said opening being extended to the inclined end of the upper portion 2 of the web of the rail, as indicated by the numeral 4, and the said portion is reduced and is not dove-tailed, so that the slots or depressions 3 and 4, while forming a continuous passage, gradually vary in width from the end thereof provided in the web 5 of the rail to the head of the rail. The head of the rail, directly to the rear of its dove-tailed slot or depression 3 is formed with a downwardly and forwardly inclined opening 4, the said opening passing through the depression 3, so that when a straight element is inserted within the portion 5 of the depression 3, the end of said element will project beyond the inclined end 2 of the upper portion of the web, or the front thereof. The inclined end 2 has its lower portion rounded at 6, and is continued horizontally

straight, as at 7, for a suitable distance, the said edge 7 being disposed approximately central of the web proper, and is centrally provided with a longitudinally extending groove 8. The horizontally straight wall 7 terminates with the upwardly extending edge 9 of a hook 10, the said hook being formed by the web of the rail and its uppermost portion is disposed a suitable distance below the plane of the underface of the head of the rail R'. The hook 10 is approximately one-half of its length formed with a groove or depression 11 which is arranged upon the upper edge 9 of the said hook and which communicates with the groove or depression 8. The point or nib of the hook, which is designated by the numeral 12, is disposed below the plane of the horizontally extending portion or edge 7 of the web, and the lower face of the hook is continued in a rounded wall 13 from its nib to its juncture with the base flange of the rail. The base flange terminates in a plane with the terminal of the rounded wall 13, and the said base flange has its ends to the opposite sides of its hook provided with dove-tailed slots 14 and 15 respectively.

The rail R' has its base flange at its end, and to the opposite sides of its web formed with dove-tailed projections 16 and 17 respectively which are adapted to be received within the dove-tailed slots or depressions 14 and 15 of the rail R when the rail ends are assembled, and the web of the said rail 20 has its lower portion formed with an upwardly curved member 18 which is adapted to agree with the curved portion 13 of the hook 10 and the said curved portion is continued rearwardly in the web and abuts with the upper wall or edge 9 of the hook 10 as well as with its nib 12. The wall or edge 19 terminates in a horizontally straight edge 20 which is shaped to agree with the horizontally straight portion 7 of the rail R, and the said edge 20 terminates in a rounded corner 21 from which the web is extended at an angle, as indicated by the numeral 22, which agrees with the angular portion 2 of the rail R, and also agrees with the inclined end 23 of the head of the rail R'. The inclined head is centrally formed with an enlargement in the form of a knob designated by the reference character 24 and has its front face gradually decreasing as 110 designated by the character 25, said enlargement or knob being formed upon the meet-

ing face of the web extension of the rail R' and further the said web extension is provided with an orifice 26' at a point directly below the knob or enlargement 24. 5 The edge 20, as well as a portion of the curved edge 19 is formed with a rib 26, the said rib being shaped to be received within the depressions 8 and 7 of the rail R. The rib 26 is preferably V-shaped in cross section. In assembling the rail R' has its end arranged at an angle to that of the rail R to bring the edge of its rounded portion 18 into contact with the rounded portion 13 of the rail R. When in such position, the 10 edge 13 serves as a fulcrum point for the rounded edge 18, so that the head and extending web of the rail R' may be swung over the hook 10, and horizontally straight edge 7 as well as the beveled ends of the head and web into engagement with the beveled end 1 of the rail R and the beveled or inclined transverse wall 2 of the rail R. This movement of the rails also forces the 15 enlargement or knob 24 as well as rib 26 and the dove-tailed extension 16 and 17 into engagement with the recesses and grooves provided for their reception. When the rails are assembled, a securing element, 20 in the nature of a threaded member 27, may be passed through the opening in the head of the rail R to bring its threaded shank into engagement with the orifice 26' of the web extension of the rail R', it being understood that the member 27 is either headless or has 25 its head disposed in a countersunk depression provided in the upper face of the head of the rail R-R, and also that the threaded member 27 has its end provided with the usual slot for the reception of a screw driver 30 or like instrument for rotating the same.

It will be noted that in constructing a joint in accordance with my invention, two of the ordinary rails are employed, and their heads, webs and base flanges are cut to 45 provide the interlocking elements for the joint, and from the above description, taken in connection with the accompanying drawings the simplicity of the device as well as the advantages thereof will, it is thought, be 50 perfectly apparent to those skilled in the art to which such inventions appertain without further detailed description.

I have found it desirable to provide the end of the base flange of the rail R, between 55 the slots 14 and 15, with a knob 100 which is substantially in the shape of a key-stone and has its upper wall rounded to its angular sides. I also provide the end of the base flange of the rail R', below the curved member 18 and between the projections 16 and 60 17, with a depression or pocket 101 which has its walls shaped to conform with and which is adapted to snugly receive the key-stone knob 100, when the rail ends are assembled.

Having thus described the invention, what I claim is:

1. In a rail joint, two rails, one of said rails having a web extension having its top surface grooved for a portion of its length, 70 said web being formed to provide a hook, the second rail having a projecting head and web, the web of the second mentioned rail being cut to receive the projecting end of the hook of the first mentioned rail and provided along its bottom surface with a V-shaped rib adapted to be received in the groove of the first mentioned web, and means for retaining the rail ends against lateral or longitudinal movement. 80

2. In a rail joint, two rails, one of said rails having a web extension, said extension formed to provide a hook and having its top surface grooved longitudinally, the said second rail having a projecting head and web, 85 the web of the second mentioned rail being cut to receive the projecting end of the hook of the first mentioned rail and provided on its bottom surface with a longitudinally disposed V-shaped rib, said rib being adapted 90 to be received in the groove of the first mentioned web, means for retaining the rail ends against lateral or longitudinal movement, and means extending through the head of the first mentioned rail and adapted to enter an 95 aperture in the front face of the second web for permanently locking the rails together.

3. In a rail joint, two rails, one of said rails having a web extension which has its terminal formed to provide a hook, the second rail end having a projecting head and web, the web of the second mentioned rail being cut to receive the projecting end of the hook of the first mentioned rail, and means comprising interlocking tongues and grooves 100 between the rail ends for retaining the joint against lateral or longitudinal movement, said last named means also including a knob or keystone configuration formed on the abutting surface of one rail and adapted to 110 be seated in a depression having its walls shaped to conform with the configuration of the keystone formed in the other of said rails. 105

4. In a rail joint, two rails, one of said rails having a slotted head and a web extension which has its end formed to provide a hook, the second rail end having a projecting head, and a web extension, the web of the second rail being cut to receive the 115 projecting end of the hook of the first mentioned rail and provided in its free terminal portion with an aperture, means integrally formed with the rail ends for retaining the joints against lateral or longitudinal movement, and means passing through the head of the first mentioned rail and extending beyond the front walls of its slot and adapted to enter an aperture formed in the terminal of the second mentioned web for per- 120 125 130

manently retaining the two rails interlocked.

5. In a rail joint, two rails, one of said rails having a slotted head portion and a web extension which has its end formed to provide a hook, the second rail end having a projecting head and web, the web of the second rail being cut to receive the projecting end of the hook of the first mentioned rail and provided in its free terminal portion with an aperture, means integrally formed with the rail ends for retaining the joint against lateral or longitudinal movement, and adjustable means passing through the head of the first mentioned rail and extending beyond the front walls of its slot and adapted to enter the aperture formed in the terminal of the second mentioned web for permanently retaining the rails interlocked.

6. In a rail joint, two rails, one of said rails having a slotted head portion having an aperture therein and a web extension

which has its end formed to provide a hook, the second rail end having a projecting head and web, the web of the second rail being cut to receive the projecting end of the hook of the first mentioned rail and provided in its free terminal portion with an aperture, means integrally formed with the rail ends for retaining the joint against lateral or longitudinal movement, and a threaded member adjustably mounted in the aperture of the head of the first mentioned rail and of such length to extend forwardly of the slot, the extended portion of said threaded member adapted to enter the aperture formed in the terminal of the second mentioned web for permanently retaining the two rails interlocked.

In testimony whereof I affix my signature in presence of two witnesses.
